DESIGN FOR A HYDROPLANE

Paul S. Lubienski, Alexandria, Va.

Application November 25, 1944, Serial No. 116,551

Term of patent 14 years

(Cl. D71—1)

To all whom it may concern:

Be it known that I, Paul S. Lubienski, a citizen of the United States, residing at Alexandria, and State of Virginia, have invented a new, original, and ornamental Design for a Hydroplane, of which the following is a specification, reference being had to the accompanying drawings, forming part thereof.

In the drawings:

Figure 1 is a perspective view of a hydroplane, showing my new design,

Figure 2 is a side elevational view,

Figure 3 is a rear elevational view, and

Figure 4 is a top plan view.

I claim:

The ornamental design for a hydroplane, as shown.

PAUL S. LUBIENSKI.
